WHIPPLETREE

Alton Strickland, Middlesex, N. C.

Application January 12, 1939, Serial No. 250,610

4 Claims. (Cl. 278—90)

My invention relates to improvements in whippletrees, and particularly to means affording adjustability as to width and compensatory action between the component parts by reason of flexibility, and an important object of my invention is to provide a simple, efficient, and practical arrangement of the character indicated which provides for greater efficiency in the operation of animal drawn vehicles.

Other important objects and advantages of my invention will be apparent from a reading of the following description taken in connection with the drawing, wherein for purposes of illustration I have shown a preferred embodiment of my invention.

In the drawing—

Figure 1 is a general top plan view of the embodiment.

Figure 2 is a longitudinal sectional view taken through Figure 1 approximately on the line 2—2 and looking upwardly in the direction of the arrows.

Figure 3 is a transverse vertical sectional view taken through Figure 1 approximately on the line 3—3, and

Figure 4 is a transverse vertical sectional view taken through Figure 1 approximately on the line 4—4.

Referring in detail to the drawing, the numeral 5 generally designates the improved whippletree as a whole, and this is composed of the transverse bar 6 which is adjustable as to length and consists of upper and lower L-shaped members 7, 8 formed with longitudinally spaced holes 9, in the bar 7 and holes 10 in the bar 8, the foot portions of the said L-shaped bars being turned at their ends to provide eyes 11, 12, respectively, retaining respective draft rings 13, 14. Between the said foot portions extends the rod 15 which is tapered toward its opposite ends, the said opposite ends being provided with slots 16 which slidably receive the foot portions of the respective bars 7 and 8. Embracing the center portion of the rod 15 and loosely spaced therefrom is the small loop 17 of the draft fixture which is generally designated 18 and which includes the larger diameter loop 19 which is attachable to the vehicle (not shown). Between the loops 17 and 19, the fixture 18 is traversed by a bolt 20 which also traverses a registering pair of the holes 9 and 10 in the respective bars 7 and 8. It is obvious that by changing the bolt to different pairs of registered holes the device of the invention may be adjusted to correspondingly different widths, while substituting a different length of rod 15 in

accordance with the adjustment, the engagement of the slots in the ends of the rod 15 with the foot portion of the bars 7 and 8, keeping the bars properly spread and aligned without rigidity. It is also obvious that the connection between the draft fixture 18 and the elements described is relatively flexible inasmuch as the same can pivot on the axis of the bolt 20 and movement is provided for between the loop 17 of the fixture 18 and the rod 15. Further, a certain amount of 10 sliding movement of the rod 15 along and relative to the foot portions of the bars 7 and 8 as well as a limited amount of lateral relative motion, are provided for by the construction and arrangement of the parts described. 15

Although I have shown and described herein a preferred embodiment of my invention, it is to be definitely understood that I do not desire to limit the application of my invention thereto, and any change or changes may be made in the 20 materials and in the structure and arrangement of the parts, within the spirit of the invention and the scope of the subjoined claims.

Having described the invention, what is claimed as new is:

1. A whippletree comprising a pair of longitudinally overlapping bars forming a cross member, said bars being formed with longitudinally spaced holes, a pivot bolt transversing a selected pair of the holes in the bars, said bars having laterally extending portions on their outer ends, a spacer rod arranged substantially parallel to said cross member, said spacer rod being formed in its opposite ends with slots slidably receiving said laterally extending portions, a draft connection comprising a first loop loosely encircling said spacer rod and a second loop extending on the opposite side of said cross member, said draft connection having a portion between the loops pivotally connected to said cross member by said 40 pivot bolt. 35

2. A whippletree comprising a pair of longitudinally overlapping bars forming a cross member, said bars being formed with longitudinally spaced holes, a pivot bolt transversing a selected 45 pair of the holes in the bars, said bars having laterally extending portions on their outer ends, a spacer rod arranged substantially parallel to said cross member, said spacer rod being formed in its opposite ends with slots slidably receiving said 50 laterally extending portions, a draft connection comprising a first loop loosely encircling said spacer rod and a second loop extending on the opposite side of said cross member, said draft connection having a portion between the loops 55

pivots connected to said cross member by said pivot bolt, draft rings on the terminals of said laterally extending portions.

3. A whippetree comprising a pair of longitudinally aligned bars in overlapping relation forming a cross member adjustable as to length, said bars being formed with longitudinally spaced registerable holes, a vertical pivot bolt passing through registered holes selected in each bar and securing said bars together for swinging on the axis of said vertical pivot bolt, forwardly projecting draft arms on the outer ends of said bars, a relatively rigid stretcher bar positioned forwardly from and substantially parallel to said cross member, said stretcher bar being formed in its opposite ends with slots slidably receiving intermediate portions of said draft arms with the inner ends of the said slots arranged to prevent undue laterally inward movement of said draft arms toward each other, and a draft connection comprising an element traversed by said vertical pivot bolt and thereby pivotally mounted on said cross member, said element having a rear part extending rearwardly from said cross member for connection with a drawn vehicle, said element further having a forward part extending forwardly from said cross member, said forward part comprising a loop loosely embracing said stretcher bar.

4. A whippetree comprising a pair of longitudinally aligned bars in overlapping relation forming a cross member adjustable as to length, said bars being formed with longitudinally spaced registerable holes, a vertical pivot bolt passing through registered holes selected in each bar and securing said bars together for swinging on the axis of said vertical pivot bolt, forwardly projecting draft arms on the outer ends of said bars, a relatively rigid stretcher bar positioned forwardly from and substantially parallel to said cross member, said stretcher bar being formed in its opposite ends with slots slidably receiving intermediate portions of said draft arms with the inner ends of the said slots arranged to prevent undue laterally inward movement of said draft arms toward each other, and a draft connection comprising upper and lower sections positioned above and below said cross member, said upper and lower sections being traversed by said vertical pivot bolt and thereby pivotally mounted on said cross member, said sections having rear parts extending rearwardly from said cross member for connection with a drawn vehicle, said sections having forward parts extending forwardly from said cross member, said forward parts being connected together at their ends to form a loop loosely embracing an intermediate portion of said stretcher bar.

ALTON STRICKLAND. 30
